CLOSURE FOR AN INSULATED BEVERAGE CONTAINER OR THE LIKE

Alan I. W. Frank, Pittsburgh, Pa., assignor to The Alan I. W. Frank Corporation, O'Hara Township, Allegheny County, Pa., a corporation of Pennsylvania

Filed Dec. 12, 1966, Ser. No. 4,995

Term of patent 14 years

(Cl. D58—26)

FIG. 1.

FIG. 2.

FIG. 3.

FIGURE 1 is a top perspective view of a closure for an insulative beverage container or the like showing my new design;

I claim:

The ornamental design for a closure for an insulated beverage container or the like, as shown.
